UNITED STATES PATENT OFFICE.

ARTHUR C. NORSWORTHY, JR., OF NEWPORT NEWS, VIRGINIA.

PROCESS AND APPARATUS FOR BLEACHING PEANUTS.

Application filed March 21, 1927. Serial No. 176,976.

The invention relates to an improved process and apparatus for bleaching raw peanuts in hull.

This invention has for its object the operation of bleaching raw peanuts in hull form. The bleaching of raw peanuts is designed to remove impurities and foreign matter, such as stains, mold, mildew, smut and bacteria, all of which the peanut may be affected with, 10 due to exposure to weather during the time the peanuts are maturing.

The bleaching and removal of such afflictions as the peanut may possess is accomplished by subjecting it to a chamber of confined hypochloric acid gas, which is a powerful bleaching agent and also a disinfectant.

I have found that hypochloric acid gas gives very satisfactory results as a bleaching agent for raw peanuts in hull, when confined with peanuts in such a manner as the drawings show, where the bleaching gas is formed by a mixture of steam and chlorine gas, furnished from an outside source. When subjected to such a treatment even the 20 darkest and most impure raw peanuts in hull are automatically bleached and purified.

A further object of the invention is to provide efficient apparatus of simple structure for bleaching purposes.

30 Other objects will appear from the accompanying description, drawings and claims.

Prior to this invention raw peanuts in hull have never before been bleached successfully by a chemical process. All peanuts which 35 are sold in hull are not bleached and purified in a chemical way before leaving the factory, but they are whitened by a form of powder which is very expensive and extremely injurious to the persons who work in the powdering rooms.

The invention consists in the features, combination and arrangement of parts hereinafter described and particularly pointed out in the claims.

45 In the drawings

Figure 1 is a perspective elevation of the machine.

Figs. 2, 3, 4 and 5 are views of details.

Referring to the accompanying drawing, 50 Fig. 1 represents a sectional elevation of a peanut bleaching apparatus, constructed in accordance with the invention, the peanuts

being conveyed to a gas chamber by a common slide conveyor 19 which catches them as they dump from the carrier belt A. The 55 peanuts as they enter the gas chamber are freed of any grit or dirt by a large fan 22, which not only cleans them, but is so disposed as to prevent the bleaching gas from escaping from the gas chamber, by way of 60 the peanut inlet.

The peanuts falling into gas chamber are caught on the vibrating shakers 1 and 2 and are gradually shaken through gas chamber B during which time the peanuts are attacked 65 by the bleaching gas, preferably hypochloric acid gas, which automatically bleaches them, the bleaching gas being furnished by outside source and conveyed to gas chamber through gas mixer 10 and cooler 13, and on to gas 70 chamber by pipe 5, the gas being diffused into the gas chamber by a series of horizontally disposed pin hole diffusion tubes 11 which are mounted between shakers 1 and 2. Shakers 1 and 2 each comprise a set of two 75 screen shakers M connected rigidly together by steel rods N.

Shakers 1 and 2 are mounted in the gas chambers for the purpose of regulating the flow of peanuts through said chamber, the shakers being fastened to frame C by spring steel hangers D and operated respectively by shaker arms 20 and 21 which are connected to shafts 8 and 8' which extend through the side of the bleaching machine. The shaker arms 20 and 21 are connected at 80 their upper ends to members P and P' of the shakers. The vibrating motion of the shaking screens is obtained by variable couplings F on said drive shafts 8 and 8'. The 85 shakers preferably have an oscillation of about one-quarter inch which gives the peanuts a regular flow through the chamber. The cross bars E in the shakers are preferably made adjustable in the shakers to regulate the distance between them. They may be spaced at any distance desired according to the amount of peanuts desired to be bleached at a given time, so as to regulate 90 the flow of peanuts.

A view of the shaker arm 20 and 21 is shown in Fig. 2 and Figs. 3 and 4 show the pulley G and shaft 8 with eccentric K providing the variable coupling F with shaker 100.

arm 20. This gives a clear idea of how the oscillating motion of the shakers is obtained. The bottom of the gas chamber 9 is shown, including a broken section, giving a detail view of the sheet metal lining, the asbestos middle lining and the heavy timbers constructing the wall of the housing.

The peanuts as they fall from shakers are completely bleached. They are caught in a perforated angular bucket 16 and are conveyed outside to carrier belt 14. The perforated bucket 16 is constructed of sheet metal with small holes 16' by which the condensation of the bleaching gas may easily pass through to the bottom of the bleaching machine.

The fan 3 at the bottom of the peanut outlet prevents the bleaching gas from escaping through the peanut outlet and forces the stale gas and condensation down to drain bucket 4.

Drain bucket 4 is constructed at the bottom of the gas chamber for the purpose of collecting the condensation which may exist within said bleaching machine. Drain pipe 7 is connected to drain bucket in order to free the same of the said stale gas and condensation. The drain bucket is of angular construction, made of sheet metal, this being a base for the bleaching machine.

The novel arrangement of screen shakes into sets placed one above the other with gas diffusing means disposed between the sets and the novel means for supporting the sets upon hangers together with the effective means for shaking the sets of screens provides an efficient and extremely effective apparatus for bleaching peanuts and the like, the gas being circulated thoroughly through the peanuts as they gradually descend through the shaking screen.

This invention is not to be understood as restricted to the detail drawing or description since these may be modified within the limit of the appended claims without departing from said invention.

I claim:

1. In combination in apparatus for bleaching and purifying raw peanuts in hull and the like, a housing enclosing a gas chamber having an inlet at its upper end and an outlet at its lower end, shaking means mounted in said gas chamber comprising an upper set of screen shakes and a lower set of screen shakes, said sets of shakes being aligned vertically, each set comprising upper and lower horizontally disposed screen shakes rigidly connected together, and gas diffusing means disposed between said upper and lower sets.

2. In combination in apparatus for bleaching and purifying raw peanuts in the hull and the like, a housing enclosing a gas chamber, said chamber having an inlet at

its upper end and an outlet at its lower end, shaking means comprising sets of screen shakes disposed in said gas chamber, one above the other, each set comprising upper and lower horizontally disposed screen shakes, means for connecting the screen shakes of each set rigidly together and hanger members connecting said sets to said housing, means for oscillating each set of shakes and gas diffusing means disposed between said upper and lower sets.

3. In combination in apparatus for bleaching raw peanuts in the hull and the like, a housing enclosing a gas chamber, said chamber having an inlet at its upper end and an outlet at its lower end, shaking means comprising sets of screen shakes disposed in said gas chamber, one above the other, each set comprising upper and lower horizontally disposed screen shakes, means for connecting the screen shakes of each set rigidly together, hanger means movably connecting said sets to said housing, means for independently oscillating each set of shakes comprising rods each secured at one end to a set and extending horizontally into eccentric engagement respectively with drive shafts at right angles thereto, and gas diffusing means comprising a series of perforated horizontally disposed gas diffusing pipes mounted between said sets of shakes and having a common gas supply pipe.

4. Apparatus according to claim 3 in which said screen shakes are composed of a frame and a series of spaced cross rods 100 adjustably mounted in said frame for regulation of the space between them.

5. In combination in apparatus for bleaching raw peanuts in the hull and the like, a metal and asbestos lined housing enclosing a gas chamber, said chamber having an inlet at its upper end and an outlet at its lower end, means for conveying and delivering peanuts to said inlet, a fan mounted on the housing at said inlet to clean the entering peanuts of dust and to prevent the escape of gas from said chamber, a similar fan at the outlet for preventing escape of gas, means for conveying away bleached peanuts discharged from said outlet, gas supplying and diffusing means horizontally disposed centrally of said gas chamber, shaking means comprising a set of upper and lower screen shakes rigidly secured together above said diffusing means, and a similar set below said diffusing means, hangers for removably securing said sets to said housing, and means for oscillating said sets.

6. In apparatus according to claim 5, a 125 perforated angular bucket disposed in said gas chamber beneath said shakes, said bucket being substantially funnel-shaped and having its outlet directed and extending to the outlet of the gas chamber, and a 130

drain bucket disposed beneath said perforated bucket to form a bottom for the gas chamber, and having an outlet pipe to carry off stale gas and condensation.

5 7. The method of bleaching raw peanuts in the hull, which consists in agitating the peanuts in a series of successive stages and

continuously treating the peanuts with hypochloric acid gas introduced intermediate the said stages. ¹⁰

In testimony whereof, I affix my signature.

ARTHUR C. NORSWORTHY, JR.
